Patented Feb. 2, 1971

219,834

LENS FOR AUTOMOTIVE LIGHT

Charles J. Newman, Madison, Ind., and Elbert J. Lucas, Andalusia, Ala., assignors to The Grote Manufacturing Company, Madison, Ind.

Filed May 8, 1969, Ser. No. 17,069

Term of patent 14 years

Int. Cl. D12—99

U.S. Cl. D48—32

FIG. 1 is a view in perspective showing a lens embodying the invention.

FIG. 2 is a plan view thereof.

FIG. 3 is an end elevational view thereof.

FIG. 4 is an inverted plan view thereof.

FIG. 5 is a view thereof in section on the line 5—5 of FIG. 2.

FIG. 6 is a side elevational view thereof.

FIG. 7 is a fragmentary bottom perspective view thereof on an enlarged scale.

We claim:

The ornamental design for a lens for automotive light, as shown.
